UNITED STATES PATENT OFFICE.

DANIEL FORBES, OF BROOKLYN, NEW YORK.

DESIGN FOR A CUT-GLASS DISH.

SPECIFICATION forming part of Design No. 22,663, dated August 1, 1893.

Application filed May 10, 1893. Serial No. 473,732. Term of patent 3½ years.

To all whom it may concern:

Be it known that I, DANIEL FORBES, a citizen of the United States, residing at Brooklyn, in the county of Kings and State of New York, have invented and produced a new and original Design for a Cut-Glass Dish, of which the following is a specification.

Reference is to be had to the accompanying drawings forming part of this specification, in which—

Figure 1 is a plan view of a glass dish showing my design, and Fig. 2 is a sectional side elevation of the same.

The leading feature of my design consists in a five sided figure A, having each apex

connected by two curved and crossing lines B, with the two opposite apices as shown. From each apex also leads a curved line C to the second following apex and these lines B and C, form five sided spaces ornamented by rosettes D. The lines B also form a central space ornamented by a rosette E.

I claim—

The design for cut glass dishes as herein shown and described.

DANIEL FORBES.
